UNITED STATES PATENT OFFICE.

LADBROOK H. FREEMAN, OF CLEVELAND, OHIO, ASSIGNOR TO THE GUGGENHEIM LAUNDRY MACHINERY COMPANY, OF CLEVELAND, OHIO, A CORPORATION OF OHIO.

LAUNDRY-MACHINE.

1,220,620.

Specification of Letters Patent. Patented Mar. 27, 1917.

Application filed April 28, 1913. Serial No. 764,063.

To all whom it may concern:

Be it known that I, LADBROOK H. FREEMAN, a citizen of the United States, residing at Cleveland, in the county of Cuyahoga and State of Ohio, have invented certain new and useful Improvements in Laundry-Machines, of which the following is a specification.

This invention relates generally to laundry dry machinery and particularly to safety appliances utilized on such machines.

More specifically the invention relates to a safety appliance for body and sleeve ironers and it comprises mechanism in the path 15 of the hands of the operator for disconnecting the power of the pressing mechanism when the hand of the operator reaches the danger point.

The invention may be further briefly summarized as consisting in the construction and combination of parts hereinafter set forth in the following description, drawings and claims.

Referring to the drawings, Figure 1 is a front elevation of a body and sleeve ironer equipped with the appliance; Fig. 2 is an end view looking from the right to left of Fig. 1; Fig. 3 is an enlarged detail view of a portion of the machine taken approximately on the line 3—3 of Fig. 1; Fig. 4 is a rear elevation of the machine; and Fig. 5 is a top plan view.

In carrying out the invention any preferred form and construction of machine 35 may be provided with my improved safety appliance but I have shown a type of machine which is adaptable for the device, and the machine comprises a standard 1 provided with a main ironing roll shaft 2, 40 mounted in bearings 2' and 2'', a main ironing roll 3, a presser roll shaft 4, a presser roll 5, and suitable mechanism including gears 6, 7, 8 and 9 for driving the ironing roll shaft 2 from a suitable motor 10. The 45 presser roll shaft 4 has mounted on it a pair of arms 11 and 12 keyed to a shaft 13 upon which the pinion 6' and the gear 7 are loosely mounted, the pinion 6' and the gear 7 being attached together.

50 Suitable mechanism is provided for swinging the shaft 4, and it comprises a magnet 14 secured to the standard 1, and having an armature 15 secured to a lever 16 pivoted in a bracket 17 secured to the frame and 55 having its opposite end engaging a rod 18 extending up into a suitable socket 19 in

the arm 12 near the outer or free end, and the operation of this part of the mechanism is such that when the armature 15 is drawn down toward the magnet the presser roll 5 is moved into engagement with the ironing roll. A suitable gear 20 is mounted upon the shaft 4 and when the presser roll 5 is in engagement with the ironing roll this gear meshes with a pinion 21 upon the ironing roll shaft 2.

Any suitable switch mechanism may be provided for controlling the supply of current to the magnet but I have shown a construction which is effective, and this 70 mechanism comprises a pair of contacts 22, and a movable contact holder 23 carrying a pair of contacts 24. The holder 23 is mounted upon an arm 25 provided with a treadle 26 mounted in a suitable bracket 27 75 secured to the frame. When the treadle is depressed, the switch is closed and current is supplied to the magnet.

The type of machine already described does not form any part of this invention, except so far as its features enter into the combination, but the invention itself resides in the combination of this machine, or any type of ironing machine, with a safety appliance and in the features of the safety appliance itself, and this appliance will now be described.

Secured to a part of the main standard or any stationary part, as to the bearing 2' of the main shaft 2, is a bar 28 extending 90 out beyond the end of the ironing roll 3. Mounted upon this bar 28 and near the ends of the ironing roll 3 are bearings 29 which support a rock shaft 30 extending over the bearing 2' of the ironing roll shaft 2, as shown, and provided with a contact arm 31 rigid with the shaft. This contact arm carries at its outer end a contact holder 32 provided with a pair of carbon contacts 33 held in the holder by set screws 34. The contact holder is insulated from the arm 31. The arm 31 carries a strip 35 pivotally mounted on the arm and adapted to swing over a fixed portion of the bearing 2' and hold the arm with the contacts elevated. The contacts 33 coöperate with contacts 36 mounted in a contact holder 37 secured on a fixed arm 38 mounted upon a fixed part of the frame or standard.

Rigidly secured to the shaft 30 and beyond 110 the ends of the ironing roll 3 are arms 39 and 40, carrying at their lower ends a trip

roll 41. The arms 39 and 40 and the roll are arranged so that when the arm 31 is rocked, so that its contacts 33 are in engagement with contacts 36, as is shown in Fig. 2, the 5 trip roll 41 stands out just above the surface of the presser roll 5, as is shown in Fig. 2, and in the path of the fingers of the operator, the trip roller 41 rolling upon the surface of the article operated upon 10 and against the periphery of the presser roll 5. This position of the trip roller and the switch takes place when the trip 35 is in the position shown in Fig. 2. In order to cause the parts to normally assume this 15 position, a spring 42 is coiled about the shaft 30 and has one end extending under the arm 39 with the other end passing under the edge of the bar 28. The spring however may be secured in any suitable 20 manner to bring about the result.

In operation, the motor drives the ironing roll shaft 2 and the ironing roll 3. When the operator presses the treadle current is passed through the magnet and the 25 presser roll is brought into position, the operator having previously started the article upon the pressing roll. In the meantime, however, the gears 20 and 21 cause the presser roll to be driven with the ironing 30 roll. The operator then feeds the article through and in case a hand or a finger should pass too far the trip roller 41 is engaged, causing the shaft 30 to be rocked in a counter clockwise direction, as shown in Fig. 2, 35 when the contacts 33 and 36 are broken and the trip 35 will engage on the top of the bearing 2' and hold the switch broken or the contacts out of engagement. This switch is placed in the magnet circuit so that 40 when the switch is broken the magnet circuit is broken, causing the release of the armature 15 and the dropping of the presser roll 5, irrespective of the fact that the operator may have his foot upon the treadle 26. 45 The contact operated by the trip may also operate to control the supply of current to the driving motor. To restore the circuit, the trip 35 is rocked by hand so as to move out of engagement with the bearing and 50 into the position shown in Fig. 2.

Having described my invention, I claim:—

1. In combination, a platen member, a presser member, electrically operated means for bringing about a pressure between said 55 members, and means in the entrance to said presser members for breaking the circuit of said electrical means, and co-extensive with the pressing members.

2. In combination with a stationary roll, 60 a presser roll, means for driving said rolls, means for creating a pressure between said rolls, and a safety appliance for controlling the operation of the pressure creating means,

and comprising a roll in the entrance to said rolls and adapted to be operated by the hand 65 of the operator.

3. In combination with a stationary roll, a presser roll, means for driving said rolls, electrical means for bringing about a pressure between said rolls, and a safety appliance 70 for releasing said pressure and comprising a roll in the entrance to said rolls and adapted to be operated by the hand of the operator, and a switch for said electrical means actuated by said roll. 75

4. In combination with a stationary roll, a presser roll, means for driving said rolls, electrical means for bringing the presser roll into engagement with the stationary roll, a switch for controlling said pressure means, 80 and a trip frame swung over the stationary roll and having a trip portion in the entrance to said rolls and adapted to be operated by the hand of the operator and adjacent to the presser roll. 85

5. In combination with a stationary roll, a presser roll, means for driving said rolls, electrical means for moving the presser roll into engagement with the stationary roll, and a safety appliance in the entrance to 90 said rolls and adapted to be operated by the hand of the operator and comprising a trip frame suitably mounted and having a trip portion in the path of the hand of the operator and co-extensive with the stationary 95 roll, a switch controlling the electrical presser moving means, connections between said switch and the trip frame whereby upon the operation of the trip frame the switch is open, and means for holding said trip 100 frame in operative position with said switch closed.

6. In combination with a stationary roll, a presser roll, means for driving said rolls, electrical means for moving the presser roll 105 into engagement with the stationary roll, and a safety appliance in the path of the hand of the operator and comprising a trip frame suitably mounted and having a trip portion in the entrance to said rolls and 110 adapted to be operated by the hand of the operator and co-extensive with the stationary roll, a switch controlling the electrical presser moving means, connections between said switch and the trip frame whereby upon 115 the operation of the trip frame, the switch is open, and a latch for holding said trip frame in operative position with said switch closed.

In testimony whereof I affix my signature 120 in presence of two witnesses.

LADBROOK H. FREEMAN.
